DESIGN FOR A CRULLER

Norman L. Orme, Jr., Houston, Tex.

Application July 29, 1941, Serial No. 102,542

Term of patent 14 years

To all whom it may concern:

Be it known that I, Norman L. Orme, Jr., a citizen of the United States, residing in Houston, in the county of Harris, State of Texas, have invented a new, original, and ornamental Design for a Cruller, of which the following is a specification, reference being had to the accompanying drawing, forming a part thereof.

In the drawing,
Fig. 1 is a perspective view of a cruller showing my new design, and
Fig. 2 is a transverse sectional view of the same.
I claim:
The ornamental design for a cruller, as shown.

NORMAN L. ORME, JR.
